REVOLVER THUMB REST SAFETY

Maurice Hansen, San Mateo, Calif., assignor to
Samuel I. Keene, San Francisco, Calif.

Application November 1, 1949, Serial No. 124,860

2 Claims. (Cl. 42—66)

1

This invention relates to a safety device for a hand gun, and has for one of its objects the provision of simple and positive means for rendering a hand gun safe, but which means is so positioned that in the normal movement of bringing the hand gun to a firing position the operator will prepare the hand gun for instant firing by the thumb of the hand that grasps the butt.

Another object of the invention is the provision of a thumb rest that combines the function of a "safety" device, and which thumb rest is so mounted on the hand gun as to be movable under downward pressure of the thumb of the butt grasping hand from a "safe" position preventing actuation of the cocking piece of the firearm to a "ready" position freeing said cocking piece for actuation, and which thumb rest is in the correct position for supporting the thumb during firing of said hand gun when in said "ready" position.

In the employment of a "safety" device on a hand gun, it is important that the safety device be one that is very quickly actuated by the hand that grips the butt and that no possible uncertainty exists as to its operation or as to how it operates.

In conventional service revolvers, for example, whether the hammer or cocking piece is exposed or not, the revolvers may be fired by merely pulling the trigger. The cocking piece is retracted and released by such pull. A revolver of this type is known as a "double-action" revolver. Where the hammer is exposed, the latter is ordinarily adapted to be retracted, or cocked, by the thumb. Heretofore the only provision made for rendering the revolver "safe" has been to release the hammer, if cocked, to its forward position, which is inadequate, inasmuch as the hammer may still be cocked and fired. With the present invention, the hand gun cannot be cocked and fired until a positive lock has been released.

It has been variously proposed that a slide, or trigger obstructing reciprocable or oscillatable element be employed, but in such instances the operator usually must employ both hands to release the safety latch, one to hold the hand gun and the other to move the safety latch, and in any event, it is not obvious to the user where the safety latch is located and exactly which is the "safe" and which is the "ready" or unlocked position. These disadvantages obviously outweigh the advantage of a safety where delay in releasing the safety may be fatal to the user.

With the present invention the safety device is so positioned as to make its operation in releasing the trigger and cocking piece certain and rapid even to a user who has no familiarity with the

2

hand gun. This ease of operation and certainty is principally in providing a movable thumb rest that is naturally engaged and moved by the thumb of the user in the natural operation of bringing the hand gun into firing position.

In the drawings, Fig. 1 is a side elevational view of a revolver with my invention thereon.

Fig. 2 is an enlarged fragmentary elevational view of the butt of the revolver of Fig. 1 with the forward hand grip and side plate removed and with the locking element indicated in cross-section.

Fig. 3 is a fragmentary side elevational view of a portion of the revolver showing the inside of the near side plate that is removed from the drawing, Fig. 2.

Fig. 4 is an enlarged fragmentary cross sectional view taken along line 4—4 of Fig. 3.

Fig. 5 is a top plan view of the safety latch removed from the hand gun, and Fig. 6 is a side elevational view of the latch of Fig. 5 as seen from the side that is against the side plate of the hand gun.

In detail, the revolver shown in Fig. 1 comprises the usual butt 1 having removable hand grips 2 at opposite sides thereof and a side plate 3 that is removably secured to a side of the frame 4 and which side plate together with the hand grip cover the firing mechanism.

The firing mechanism includes a cocking piece 5 in the form of a hammer that is retractable to cocked position against the resistance of a main spring 6. The finger retractable trigger 7 is operably connected with the cocking piece through a conventional sear (not shown), for releasing the cocking piece from cocked position.

The above structure is conventional, and in said structure the cocking piece or hammer 5 is formed with a portion 10 that projects rearwardly and downwardly from the spur 11 of the hammer that is adapted to be engaged by the thumb of the butt gripping hand for cocking the hammer and for letting the hammer down when the operator does not wish to fire the cocked piece. In most revolvers, this portion 10 functions to fill the gap that would normally occur in the frame 4 were said portion not present, when the hammer is in forward position, and said portion 10 is formed with a downwardly directed surface 12 (Fig. 2) that moves generally downwardly when the hammer is retracted.

In the present invention, one end 14 of a flat arm 15 is pivotally secured by a stud bolt 16 to the outer side of the side plate 3 at a point below the crane lock or thumb piece 17 that releasably holds the cylinder 18 against lateral swinging to

unloading position. This arm preferably is horizontally elongated and plate-like with one of its flat sides against the side plate 3 and with its upper and lower edges extending divergently from the forward end portion 14.

The side of arm 15 that faces side plate 3 is formed with a pair of laterally opening recesses 20, 21 that are spaced one above the other on an arcuate line concentric with the axis of pivot 16.

The side plate 3 is formed with a bore 25 and with a counterbore 26 that opens outwardly of the side that faces the arm 15. A pin 27 slidably extends through bore 25 and is formed with a head 28 that is adapted to move into and out of the counterbore 26. This head 28 is preferably rounded on its outer side, and an expansion coil spring 29 around the pin reacts between the head 28 and the shoulder defining the inner end of the counterbore thus yieldably urging the rounded side of the head into engagement with the arm 15. The head 28 is adapted to slide in the recess 20 when the arm 15 is swung upwardly, thereby yieldably holding the arm up, and upon application of downward pressure on the arm to swing it downwardly, the head will be more out of the recess 20 and into recess 21. In other words, the arm 15 will be yieldably held either up (as in Fig. 1) or down, and the degree of such movement from the up position to the down position is determined by the spacing between recesses 20, 21.

In order to insure against possible separation between the outer end of arm 15 (remote from pivot 16) and the side plate 3, and to positively limit the swinging of the arm about pivot 16, the side plate 3 is formed with an arcuate slot 30 (Fig. 4) that is concentric with the pivot 16. This slot is enlarged at 31 (Fig. 4) to receive the flat head 32 of a screw 34 that extends through slot 30 and that is threadedly secured in the arm 15. This screw is shouldered to prevent binding of the arm 15 yet to insure a close sliding fit between the adjacent surfaces of arm 15 and side plate 3. The head, being in enlargement 31 does not interfere with any of the trigger or firing mechanism.

The bore 25 for pin 27 positioned just below the shoulder 12 of the cocking piece is substantially in slidable engagement with the side plate 3, it will be seen that when the pin 27 projects inwardly from the side plate as seen in Figs. 2, 4, it will be in the path of travel of the cocking piece and the cocking piece or hammer will be positively locked against retraction. The trigger will likewise be locked through its conventional operative connection with the cocking piece.

When the rear end of arm 15 is swung downwardly from the position shown in Fig. 1, to the point where the head of pin 27 snaps into recess 21, the projecting end of pin 27 will be withdrawn completely until its outer end is substantially flush with the inner surface of the side plate 3, and then the cocking piece may be retracted manually or by means of the trigger. Recess 21 is of sufficiently greater depth than recess 20 to permit said retraction of the pin 27.

The rear end of arm 15 is formed with a relatively wide lateral projection 40 (Figs. 1, 5) that is adapted to form a thumb rest for the thumb of the hand that grips the butt of the hand gun. This projection or ledge preferably is slightly convexly curved on its upper surface in direction of the longitudinal axis of the hand gun, and is exactly in the correct position when the

5 rear end of the lever is swung downwardly, to support the thumb of said hand in exactly the correct position with the thumb pointing forwardly. Some hand grips now provide such a rest for the thumb which contributes to marksmanship.

10 In the present instance, when the rear end of arm 15 is up, or in the "safe" position with pin 27 locking the hammer against retraction, the ledge or projection 40 is obviously too high to correctly support the thumb, hence the natural action of the user is to push downwardly on the thumb rest upon bringing the hand gun to aiming position with the result that the rear end of the arm is swung downwardly to the correct position and pin 27 is retracted. The safety device, or arm 15, is then in the "ready" position and the hand gun may be fired by pulling the trigger or by first cocking the cocking piece by the thumb.

15 To render the revolver "safe" after firing or when the revolver is loaded and is carried, or laid away, the user merely slips the thumb of the butt-gripping hand below the ledge 40 and swings the arm 15 upwardly to "safe" position. The degree of resistance to such movement is determined by the spring 29 and the shapes of recesses 20, 21 and head 28, and is such as to prevent accidental swinging of the arm 5 while permitting intentional swinging under a force that may be readily applied by the thumb only of the hand that grips the butt.

20 By the above structure a safety device is provided that is readily and naturally manipulated by the thumb of the hand that grips the butt of the revolver or hand gun, which hand is the one that is employed in the entire shooting operation. The movement of the safety to "ready" position does not require a shifting of the thumb from a safety device back to its proper position, but instead, the actual movement of the thumb to its correct position unlocks the safety device and the thumb actuatable element becomes the thumb rest when the safety device is in the "ready" position.

25 From the foregoing explanation, it will be obvious that the hand gun is absolutely safe when the safety device is in the "safe" position, a condition not provided for in present conventional revolvers and which lack creates an ever present peril from accidental firing of a loaded hand gun.

30 However, the provision of such safety device by the present invention does not delay the rate of speed at which the user may, under extreme urgency, be required to fire the hand gun. The hand gun may be drawn, the safety moved to "ready" position, aimed, and fired with the same speed as though the safety device were not present for the reason that the safety device is automatically actuated by the normal operation of the hand and thumb in moving the hand gun to firing position without requiring any extra or additional movement, such as pushing or pulling a lever or a pin or other element and thereafter being required to withdraw the finger that has actuated such element. Nor does the present invention require the hand or any finger to continuously exert a pressure of any kind to hold a safety device in a position in which the cocking piece may be actuated.

35 40 45 50 55 60 65 70 75 It is also seen from the description that the conventional parts of the hand gun remain unchanged by the present invention. It is to be understood that the invention is not to be considered as being necessarily restrictive to the precise position of the locking pin. The pin

might be positioned elsewhere provided it functioned to prevent the cocking of the cocking piece. The illustration shows the safety device on one of the conventional makes of revolvers. Variations between standard structures would require modifications that would be obvious in order to adapt the invention to the different structures, all of which, however, are fundamentally similar. In the present instance, while the structure shown is preferable, it will be seen that the pin 27 could be positioned to obstruct the movement of the upper run of the spring 6 toward collapsed or generally downward movement, and the cocking piece would be locked. Or the side of the hammer 5 might be recessed to receive the projecting end of the pin 27 when the arm 15 was in the "safe" position and, although this would involve a slight alteration of the cocking piece, it would not constitute the adding of any element.

I claim:

1. In a revolver including a frame having a butt for grasping by the hand and a retractable cocking piece and a retractable trigger operably connected with said cocking piece for release of the latter from a retracted position upon a predetermined movement of said trigger, a thumb rest projecting laterally from a side of said frame substantially the width of the thumb of said hand and adjacent to the upper end of said butt supported on said frame for generally vertical movement from an elevated position to a lowered position and vice versa, means securing said thumb rest to said frame for said movement, said thumb rest being engageable by said thumb when in said elevated and lowered positions and when the forefinger of said hand is in trigger retracting position for effecting said movement of said thumb rest by said thumb and for supporting said thumb pointing forwardly in normal shooting position when said thumb rest is in said lowered position, a member supported on said frame for movement from a "safe" position obstructing retraction of said cocking piece when said thumb rest is in said elevated position to a "ready" position permitting said retraction of said cocking piece when said thumb rest is in said lowered position and vice versa, and means including a portion of said thumb rest rigid with the latter and in engagement with said member for causing said movement of said member upon said movement of said thumb rest from said elevated position to said lowered position, said last mentioned means including means for yieldably holding said

55

thumb rest in said elevated and said lowered positions respectively.

2. In a revolver including a frame having a butt for grasping by the hand and a retractable cocking piece and a retractable trigger operably connected with said cocking piece for release of the latter from a retracted position upon a predetermined movement of said trigger, a thumb rest projecting laterally from a side of said frame substantially the width of the thumb of said hand and adjacent to the upper end of said butt supported on said frame for generally vertical movement from an elevated position to a lowered position and vice versa, means securing said thumb rest to said frame for said movement, said thumb rest being engageable by said thumb when in said elevated and lowered positions and when the forefinger of said hand is in trigger engaging position for effecting said movement of said thumb rest by said thumb and for supporting said thumb pointing forwardly in normal shooting position when said thumb rest is in said lowered position, a member extending through said frame and supported by the latter for movement at right angles to the movement of said thumb rest from a "safe" position obstructing retractive movement of said cocking piece to a "ready" position permitting such movement, a spring yieldably holding said member in engagement with said thumb rest during said movement of said thumb rest thereover, the surface of said thumb rest adapted to be so engaged by said member being formed with a pair of recesses in which said member is adapted to be yieldably held by said spring when said thumb rest is in said elevated position and in said lowered position for releasably holding said thumb rest in said elevated and said lowered positions said recesses being respectively formed to hold said member in said "safe" position and in said "ready" position when said thumb rest is in said elevated and lowered positions respectively.

MAURICE HANSEN.
